(57) **CLAIM**

The ornamental design for a regulator bonnet, as shown and
described.

DESCRIPTION

FIG. 1 is a front, left side perspective of the regulator bonnet
showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines in FIGS. 1-7 are for the purpose of
illustrating environment, and form no part of the claimed
design.
